METER BLOCK CONNECTER

John G. Jackson and Clement W. Wolf, Detroit,
Mich., assignors to Square D Company, Detroit,
Mich., a corporation of Michigan

Original application July 22, 1931, Serial No.
552,504. Divided and this application May 9,
1932, Serial No. 610,208

3 Claims. (Cl. 173—324)

This invention relates generally to electrical equipment such as meter-test-block connectors and constitutes a division of our application filed July 22, 1931, bearing Serial No. 552,504.

6 In the accompanying drawings:

Figure 1 is a front elevation of equipment embodying our invention;

Figure 2 is a front elevation with the cover of the test block casing removed and showing 10 parts of the meter broken away;

Figure 3 is a sectional view taken on the line 3—3 of Figure 2;

Figure 4 is a rear elevation of the test block;

15 Figure 5 is a cross sectional view taken on the line 5—5 of Figure 1;

Figure 6 is a detail perspective view of one of the connectors;

Figure 7 is a section on the line 7—7 of Figure 2.

20 Referring now to the drawings, A is an electric meter; B is a test block; and C are the connecting links embodying our invention. As shown, the meter A is of conventional design and is provided at one end with a terminal chamber 1 25 containing a plurality of laterally spaced terminals 2 having longitudinally extending outwardly opening sockets 3 in the outer ends thereof. The test block B is housed within a suitable casing 4 and includes the base 5 of insulating 30 material, test links 6, 7, 8 and 9 respectively arranged in parallel relation on the front of the base, terminals 10 extending through the base at one end thereof in alignment with the links 6, 7, 8 and 9 respectively, a terminal 11 extending 35 through the base and secured to the link 6 at one end thereof, a cross-over link 12 upon the back of the base and terminally connected to one of the terminals 10 and to the terminals 11, and cross-over links 13, 14 and 15 respectively 40 upon the front of the base and terminally secured to the links 7, 8 and 9 respectively and to the three other terminals 10. The links C constituting the connectors extend through one end 45 of the casing 4 and are terminally connected to the terminals 2 and 10 respectively. As shown, these links C are stamped or pressed from sheet metal, preferably copper, and are flexible in nature. Each link C has a forked 50 or bifurcated head 17 and has a substantially straight shank 18. Preferably the furcation 19 is in line with the straight shank 18 while the furcation 20 is offset laterally relative thereto. A sleeve 21 of insulating material surrounds each shank 18 from the head 17 to a point adjacent 55 the end 22 of the shank.

In use the forked heads 17 straddle the terminals 10 and are detachably held thereon by nuts 23 threadedly engaging said terminals, while the ends 22 of the shanks are received within the sockets 3 and are held therein by set 60 screws 24 threadedly engaging the terminals 2. To accomplish this connection the forked heads 17 may be secured first to the terminals 10 and the ends 22 of the shanks may then be inserted into the sockets 3 upon moving the test block 65 casing 4 toward the terminal chamber 1 of the meter and may thereafter be secured in the sockets 3 by tightening the set screws 24. In this connection it will be noted that the links C are flat and the shanks 18 thereof have the 70 same substantially square cross sectional area throughout their length, while the sockets 3 are circular in cross section throughout their length. As illustrated in Figure 5, the construction and arrangement of the parts is such that two longitudinal edges 30 and 31 respectively of the shanks are held by the set screws 24 in engagement with spaced portions of the curved walls 75 of the sockets 3.

Thus, due to the arrangement just referred to 80 and the fact that the connectors C are formed of relatively soft copper and are inherently flexible, it is possible to accommodate the spacing of the terminals of meters to wider or narrower spacing of terminals of test blocks in a very 85 simple manner.

Moreover, with the arrangement described it 90 is possible to make practically direct connection from the meter terminals to the test block terminals and this not only permits of ready installation of the connectors C therebetween but, as will be evident from the illustration, such arrangement greatly reduces the spacing required 95 between the meter and the test block. In fact, when connectors such as C are used it is not 100 only desirable but necessary to use the particular type of test block with cross-over features as shown herein to secure the relatively opposite positioning of block terminals to meter terminals of the same polarity and sequence.

It will also be noted that the forked heads 17 105 of the connectors provide sufficient longitudinal adjustment for the connectors to permit them to straddle the test block terminals 10 without removal of the nuts 23. Thus the connection between the meter and test block may be made after both such parts have been mounted in place. Moreover, by affixing the connectors to either the test block terminals 10 or to the meter terminals 2 either the meter or the test block 110

may be connected to the other after it has been previously mounted in place. Thus the connectors C enable the meter and test block to be connected together efficiently, easily and quickly.

- 5 5 While it is believed that from the foregoing description the nature and advantages of the invention will be readily apparent, we desire to have it understood that we do not limit ourselves to what is herein shown and described 10 and that such changes may be resorted to when desired as fall within the scope of what is claimed.

What we claim as our invention is:

- 15 1. Means for electrically connecting laterally spaced terminal sockets of a meter to laterally spaced terminal posts of a test block comprising a plurality of connecting members, each member being a relatively short substantially straight stamping having an elongated narrow portion 20 for insertion into one of the terminal sockets of the meter and a flat offset portion provided with an opening for the reception of a terminal post of the test block, said opening being offset relative to the longitudinal median line of said narrow portion so that the opening may be positioned upon one side or the other of the axis of the meter terminal socket to accommodate different positions of said terminal posts relative to 25 the axes of said sockets.
- 30 2. Means for electrically connecting laterally spaced terminal sockets of a meter to laterally spaced terminal posts of a test block comprising a plurality of connecting members, each member being a relatively short substantially straight stamping having an elongated narrow portion 35 for insertion into one of the terminal sockets of the meter and a flat offset portion provided with

an opening for the reception of a terminal post of the test block, said opening being offset relative to the longitudinal median line of said narrow portion, so that the opening may be positioned upon one side or the other of the axis of the meter terminal socket, and said elongated narrow portion being formed of relatively soft material so that it may be bent to accommodate different positions of said terminal post relative to the axes of said sockets.

3. A meter connector comprising a relatively short substantially straight stamping having an elongated narrow portion for insertion into a cylindrical meter terminal socket, and a relatively wide flat offset portion having an opening therein adapted to receive the binding post of a meter test block, said opening being offset relative to the longitudinal median line of said narrow portion so that the opening may be positioned upon one side or the other of the axis of the meter terminal socket to accommodate different positions of said terminal post relative to the axis of said socket, said narrow portion having longitudinally extending edges at opposite sides thereof engageable with the curved walls 100 of said socket and provided between said edges with a substantially flat surface adapted to be engaged by a pressure producing member, the thickness of said stamping throughout its length being substantially equal to the width of the 105 narrow portion aforesaid, and said stamping being formed of relatively soft material whereby it may be bent to align the portions aforesaid with the meter terminal socket and test block binding post, respectively.
